DESIGN FOR A HAND FIRE EXTINGUISHER

Howard C. Smith, Buffalo, N. Y., assignor to Buffalo Fire Appliance Corporation, Buffalo,
N. Y., a corporation of New York

Application August 17, 1944, Serial No. 114,911

Term of patent 14 years

(Cl. D16—2)

To all whom it may concern:

Be it known that I, Howard C. Smith, a citizen of the United States, residing at Buffalo, in the county of Erie and State of New York, have invented a new, original, and ornamental Design for a Hand Fire Extinguisher, of which the following is a specification, reference being had to the accompanying drawing, forming part thereof.

In the drawing:

Fig. 1 is a top plan view of a hand fire extinguisher embodying my new design.

Fig. 2 is a side elevational view thereof.

Fig. 3 is a bottom plan view thereof.

I claim:

The ornamental design for a hand fire extinguisher, as shown.

HOWARD C. SMITH.
